UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

SHEET-FEEDING MACHINE.

1,154,407.

Specification of Letters Patent. Patented Sept. 21, 1915.

Original application filed January 24, 1914, Serial No. 814,096. Divided and this application filed September 4, 1914. Serial No. 860,204.

To all whom it may concern:

Be it known that I, HOWARD K. KING, a citizen of the United States, residing at Philadelphia, in the county of Philadelphia, 5 State of Pennsylvania, have invented a new and useful Sheet-Feeding Machine, of which the following is a specification.

My invention relates to improvements in sheet feeding machines.

10 The object is to provide improved means for separating and delivering single sheets from a bank of sheets.

The particular improvement, which is the subject-matter of this invention, is the 15 presser foot or pile drag, and the adjustable means for automatically controlling the same to suit the various requirements of sheets of characteristics; that is, sheets that are hard to comb and sheets that are easy 20 to comb.

This application is a divisional of my pending application Serial No. 814,096 filed January 24, 1914.

Referring to the drawings, which illustrate merely by way of example, suitable means for embodying my invention—Figure 1 is a side elevation showing the general arrangement of combing wheel and feeding roller operating between the upper and lower tables. Fig. 2 is a sectional elevation showing the combing roller and the air valve controlled thereby. Fig. 3 is a side elevation in part section of the pile drag or presser foot mechanism. Fig. 4 is a plan 30 of same showing the combing wheel and separating mechanism in horizontal section. Fig. 5 is a vertical section on line 5—5 of Fig. 3.

Similar numerals refer to similar parts 40 throughout the several views.

Fig. 1 shows the general arrangement of a continuous sheet feeding machine. 6 is the feed roller adapted to feed the bank of sheets from the top table 7 to the lower 45 table 8. This feeding roller or drum 6 is driven or actuated in any suitable way and under any suitable control. Such actuation and control forms no part of the present application, and therefore will not be described. The combing wheel 9 is rotated and actuated into and out of operative position by a suitably controlled means likewise forming no part of the present application.

It will be enough to state for the pur-

poses of the present application that the 55 feed roller or drum gradually moves the bank from the upper table 7 to the lower table 8 and forward upon the lower table 8 to the combing rollers 9; said roller or drum being controlled so as to keep just sufficient thickness of the bank of sheets beneath the combing wheel and that the combing wheel is operated and controlled to step the sheets forward one in advance of the other so that the top sheet is delivered to the drop 60 and feed rollers 10 and 11 which are controlled and operated to carry off said top sheet at the proper moment of the cycle. Coöperating with these instrumentalities is provided a presser foot or pile drag, preferably one for each combing wheel when two 65 combing wheels are employed.

On practically all paper, except paper that is extremely hard to comb, it is desirable to have more or less weight on the bank. 75 This weight should rest on the bank several steps or sheets back of the top sheet. They serve a double purpose; one to retard the rear or under sheets, and thus increase the separation or steps in the upper sheets 1 the 80 other purpose is to give a constant resistance to comb against, thereby making the "hard" and "soft" spots in the bank less marked. It is a well known fact that a pile or bank does not comb uniformly; frequently combs 85 quite easily in some places, and quite hard in other places; changing suddenly from one condition to the other. The drag, acting with a constant resistance, decreases the percentage of variation between the extreme 90 conditions of hard and soft places.

The pressure on the combing wheels is set to comb against the natural resistance of the paper plus the resistance caused by the pressure of the drag. On hard combing 95 paper, where only a very few sheets are acted upon at a time, it is desirable to use little or no drag weight. On paper where the combing influence extends deeper into the bank, it is desirable to use considerable 100 weight, as a resistance or drag to prevent or lessen the motion of the sheets deeper down.

The explanation given above shows the advantages gained by using the drag. However, the machine can be adjusted to 105 operate without it. In practice, the changing of the pressure due to weight or spring on the drag is one of the adjustments most

frequently made in operating the King pile feeder. It is one of the adjustments used to secure the proper length of steps in the combed-out sheets.

5 The pressure weight now under consideration is provided with a diaphragm, see Fig. 5. This diaphragm is rigidly attached to the part bearing on the bank. It also forms part of the weight. All the weight bearing 10 on the paper is direct gravity. There are two of these pressure devices complete, one back of each combing wheel. Each one is provided to carry extra weights for example, 12 and 13. However, it is expected that 15 with one of these weights on each device, practically all kinds of paper can be successfully handled.

The adjustment consists in the control of the amount of air admitted to the diaphragm head. These diaphragm heads are 20 so arranged that they are lifted when sufficient compressed air is admitted to them, the inclosed piston and piston rod remaining stationary.

25 The diaphragm or pneumatic head is rigidly secured to the sleeve 14 which carries the presser foot 15. The pin 16 is rigidly secured to the outer casing 17 which is adjustably connected with the bracket 18. 30 When air pressure is admitted to the head 19 above the diaphragm piston 20 piston rod 21 being in engagement with pin 16 it follows that the said piston rod can have no further downward movement, the result is, 35 that the diaphragm head 19, sleeve 14 and presser foot 15 are correspondingly lifted. The hollow sleeve 14 is provided with slots as at 22 to permit relative movement between said sleeve to the fixed pin 16. The 40 result is that, as the pressure is increased above the diaphragm 20, the pressure of the presser foot 15 is relieved. In this way it follows that the pressure exerted by presser foot 15 is gradually relieved as the pressure 45 in the diaphragm head increases. By this arrangement only one set of valves is necessary to control both heads. This set consists of two valves, a needle valve and a balanced piston valve. The piston valve is operated 50 by the vertical movement of the left hand combing wheel.

Rear pressure weights or drag weights.—
This valve and valve operating mechanism is illustrated in Fig. 2. The valve piston 55 23 is provided with a suitable casing having chambers connected one with the source of air supply 24 and the other connected with the diaphragm head 19. The piston 23 is adapted to establish communication between 60 the air pressure supply and the diaphragm head in one position and between the cut off of said communication and establish communication between the diaphragm head and exhaust in the other position. The piston is 65 actuated by the contact piece 25 secured on

the arm 26 which is mounted on the shaft 27. When the combing wheel is down, the valve connects the compressed air supply with the diaphragm heads. When the combing wheel is up, the valve shuts off the supply of air 70 to the diaphragm heads, and instantly exhausts the air pressure in them to the atmosphere. The compressed air, before reaching the piston valve, passes through a needle valve 28. The manual adjustment of this 75 needle valve constitutes the adjustment of the drag weight; this adjustment alone being sufficient for working from the easiest to the hardest combing papers.

For easy combing paper the needle valve 80 should be open only slightly. Under this condition, when the combing wheels go down, the drag weight is very slowly lifted, just as slowly as the operator may desire. The greater part of the weight of the drag 85 being on the paper when the combing wheels first come into action, this weight more or less rapidly becomes lighter during the combing interval.

For hard combing paper the needle valve 90 may be opened quite wide, with the result that the drag is lifted clear of the paper about the time the combing wheels reach the paper. When the valve is so adjusted, the drag weight would not have any influence 95 in retarding the combing action of the wheels.

With the needle valve the operator can quickly get any speed in lifting, from a movement barely noticeable to the quickest 100 speed required. The adjustment of the needle valve is made with the machine in operation, so that the result of any change in adjustment can be quickly seen. The adjustment of the needle valve is equivalent 105 to changing the weight of the drag; but the operation of lifting the drag, and thus changing the weight of the drag during the combing interval does more than that. Its 110 effect is to automatically take care of the hard and easy combing parts of the bank, without the operator making frequent adjustments to suit the varying conditions. The 115 explanation of how this is accomplished is as follows:—The combing wheels are arranged to remain in action upon the sheet until the sheet is brought into position under the valve trip fingers at the feed roller. If this 120 time exceeds the part of the cycle allowed to combing action, it will cause a miss in feeding, the sheet being taken away on the succeeding cycle of the machine. When the machine is properly adjusted, the normal time of combing will not exceed half of the time allowance. The hard combing parts of the 125 bank will require more than normal time; the easy parts less than normal. The weight of the drag is gradually lessened during the combing. For illustration, consider that it 130 is lifted clear of the paper at the end of the

normal or average combing time. In this case the additional combing time, when working on a hard combing place, will be under the most favorable condition, having 5 no drag resistance to comb against. On the other hand, when an easy combing place is encountered, the wheels remain down less than the normal time, perhaps half of the normal time. In this case the entire combing will be against the resistance of the drag. This increases the length of steps over what they would otherwise be. It also increases the interval of time that the wheels remain down over what it would otherwise 10 be. In other words, it shortens the long combing interval, and lengthens the short combing interval. It shortens the length of the steps that go with a hard combing place; and lengthens the steps that go with an easy 15 combing place.

It may be explained here that easy combing places tend to make short steps, more sheets being in motion; and hard combing places tend to make long steps, a less number 20 of sheets being in motion. A heavy drag resistance means less sheets in motion, while a light drag resistance means more sheets in motion. It will thus be seen that a gradually lifting drag weight effects a 25 valuable automatic balance to the combing action.

What I claim is:

1. In a sheet feeder, the combination with means for operating the combing rolls, of a pile drag, means for feeding a bank of sheets forward to the combing rolls, and means for relieving the pressure of the pile drag on the sheets during the forward feed of the latter.
2. In a sheet feeder, the combination with means for operating the combing rolls, of a pile drag resting on the sheets, means for feeding a bank of sheets forward to the combing rolls, and means for relieving the pressure of the pile drag on the sheets during the forward feed of the latter.
3. In a sheet feeder, the combination with means for operating the combing rolls of a pile drag, means for feeding a bank of sheets forward to the combing rolls, and means for relieving the pressure of the pile drag on the sheets at regular intervals during the forward feed of the latter.
4. In a sheet feeder, the combination with means for operating the combing rolls of a pile drag, means for feeding a bank of sheets forward to the combing rolls, means for applying pressure to the pile drag, and means for relieving said pressure during the forward feed of the sheets.

5. In a sheet feeding machine, a sheet supporting table, sheet actuating means, a pivotally supported bracket, a presser foot connected therewith and a supporting wheel or roller for the bracket.

6. In a sheet feeding machine, a combing wheel, a supporting bracket, a presser foot movable therein, a pneumatic head connected with the presser foot, a piston operating therein, means operated by the piston to engage the bracket arranged so that upon admission of air pressure to the head the presser foot and head are elevated.

7. In a sheet feeding machine, a combing wheel, a supporting bracket, a presser foot movable therein, a pneumatic head connected with the presser foot, a piston operating therein, means operated by the piston to engage the bracket arranged so that upon admission of air pressure to the head the presser foot is elevated, and a valve for controlling the pressure to the pneumatic head.

8. In a sheet feeding machine, a combing wheel, a supporting bracket, a presser foot movable therein, a pneumatic head connected with the presser foot, a piston operating therein, a piston rod adapted to engage the bracket arranged so that upon admission of air pressure to the head the presser foot is elevated, a valve for controlling the air pressure to the pneumatic head and a valve controlled by the combing wheel also for controlling the pressure to the pneumatic head.

9. In a sheet feeding machine, a combing wheel, a supporting bracket, a presser foot movable therein, a pneumatic head connected with the presser foot, a piston operating therein, a piston rod adapted to engage the bracket arranged so that upon admission of air pressure to the head the presser foot is elevated, a valve for automatically controlling the pressure to the pneumatic head, and an arbitrarily operated valve for regulating the amount of air pressure controlled by the first mentioned valve.

10. In a sheet feeding machine, a combing wheel, a supporting bracket, a presser foot movable therein, a pneumatic head connected with the presser foot, a piston operating therein, a piston rod adapted to engage the bracket arranged so that upon admission of air pressure to the head the presser foot is elevated, a valve for controlling the pneumatic head, and a needle for regulating the air pressure to the pneumatic head.

11. In a sheet feeding machine, a combing wheel, a supporting bracket, a presser foot movable therein, a pneumatic head connected with the presser foot, a piston operating therein, a member operated by the piston adapted to engage the bracket arranged so that upon admission of air pressure to the head the presser foot is elevated, a valve controlled by the combing wheel 120 control mechanism for controlling the pneumatic head, and a hand operated valve for adjusting the air pressure.

12. In a sheet feeding machine, the combination of a combing wheel, a presser foot, 130

a fixed support therefor, a pneumatic head connected with the presser foot, a piston therein and means operated thereby adapted to engage the fixed support, the parts arranged so that pressure in the head causes the elevation of the presser foot, a valve controlled by the combing wheel for controlling the pneumatic head, as means whereby the presser foot is elevated when the combing wheel descends and vice versa.

13. In a sheet feeding machine, the combination of a combing wheel, a presser foot, a fixed support therefor, a pneumatic head connected with the presser foot, a piston therein adapted to engage the fixed support, the parts arranged so that pressure in the head causes the elevation of the presser foot, a valve controlled by the combing wheel for controlling the pneumatic head as means whereby the presser foot is elevated when the combing wheel descends and vice versa, and a regulating valve for controlling the efficiency of said pneumatic actuation.

14. In a sheet feeding machine, the combination of a combing wheel, a presser foot, a fixed support therefor, a weighted pneumatic head connected with the presser foot, a piston therein adapted to engage the fixed support, the parts arranged so that pressure in the head causes the elevation of the presser foot, a valve controlled by the combing wheel for controlling the pneumatic head as means whereby the presser foot is elevated when the combing wheel descends and vice versa, and a regulating valve between the first mentioned valve and the pneumatic head.

15. In a sheet feeding machine, the combination of a combing wheel, a presser foot,

supporting means therefor; a pneumatic head connected with the presser foot, a piston operating therein, a member operated by the piston for engaging the supporting means whereby the presser foot and head are lifted when air pressure is admitted to the head, a valve for automatically admitting and discharging air pressure to and from the head and an arbitrarily operated valve for adjusting the air passage between the air pressure supply and the head whereby the speed of lifting the presser foot is regulated.

16. In a sheet feeding machine, the combination of a combing wheel, a presser foot, supporting means therefor, a pneumatic head connected with the presser foot and controlling its movement, an air valve acting relatively to the combing wheel actuation, for rendering the presser foot effective when the combing wheel becomes inoperative, and an adjustable regulating valve for retarding the presser foot actuation.

17. In a sheet feeding machine, the combination of a combing wheel, a presser foot, supporting means therefor, a pneumatic head connected with the presser foot, and controlling its movement, an air valve acting relatively to the combing wheel actuation, for rendering the presser foot effective when the combing wheel becomes inoperative, and a regulating valve, adapted to be adjusted while the machine is operating, for controlling the speed of presser foot actuation.

HOWARD K. KING.
